ACOUSTIC TONE EQUALIZER

Randolph P. Mercurius, Bronx, N.Y., assignor to
Rectilinear Research Corp., New York, N.Y.

Filed Apr. 26, 1965, Ser. No. 450,683
4 Claims. (Cl. 181—31)

This invention relates to audio equipment and more particularly to a sound system.

More specifically, this invention relates to sound systems of the type disclosed in my prior patents, No. 2,277,525 granted March 24, 1942, and No. 2,891,629 granted June 23, 1959, and has for its primary object the provision of an improved acoustic tone equalizer which can adequately and efficiently accommodate a capacity volume of sound emanating from both a set of dual general function speakers, and a mid-range frequency speaker.

Still another object of this invention is to provide a sound system which includes a single housing for enclosing the set of dual general function speakers and the mid-range frequency speaker and baffle devices in a compact and efficient arrangement.

Another object of this invention relates to providing an auxiliary cabinet containing two sets of low frequency range dual speakers to be optionally used with the improved acoustic tone equalizer in the single housing which can further adequately and efficiently handle the capacity volume added to that emanating from the set of dual general function speakers and the mid-range frequency speaker.

An additional object of this invention is to compartmentalize the housing so as to contain the several speakers each in a separate compartment provided with a port therefor and to provide novel baffle means in the housing that communicates both with the low frequency and mid frequency ranges speaker compartments so as to simultaneously amplify sound emanating therefrom and for directing the equalized sound waves outwardly through the ports.

Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described within the scope of the appended claims.

FIGURE 1 is a front perspective view of the housing embodying the invention;

FIGURE 2 is a rear perspective view of the housing;

FIGURE 3 is a front perspective view of a speaker cabinet unit;

FIGURE 4 is a vertical sectional view of the cabinet taken on line 4—4, FIGURE 3;

FIGURE 5 is a front perspective view of the housing and cabinet in assembled relation;

FIGURE 6 is an exploded perspective view partly in section showing details of the compartments, speaker positions and baffle construction.

Referring more particularly to the drawings, an enclosure or housing 10 made in accordance with the present invention, is of rectangular formation and is defined by side walls 12, 14; a top wall 16; a bottom wall 18, and a rear wall 20, all suitably joined together to form a box-like structure and supported on legs 22.

The side wall 12 is formed with a circular cut out or port 24, adjacent top 16 for mounting a general function speaker 25, the port 24 being covered with a grill cloth 26 in the manner known. Similarly the opposite side wall 14 is provided with a like similarly positioned port

2

28 for mounting a general function speaker 29, the port 28 being covered with a grill cloth 30.

Extending between the side walls 12, 14, slightly below the ports 24, 28, is a horizontal partition 32 dividing the housing 10 into an upper general function speaker compartment 34 and a lower mid-range speaker compartment 36.

Extending transversely across the partition 32 and adjacent one end thereof, are parallel rows of openings 38, 39. A divider wall 40 inclined with relation to the top 16 and partition 32, has its upper edge 41 secured to the top 16, see FIGURE 6, and its lower edge 42 disposed above and between the rows of openings 38, 39; the divider wall 40 separates the compartment 32 into two sound chambers 41, 42. Preferably, the inside edge of the divider 40 and partition 32 are secured to the rear wall 20.

Below the partition 32, the side wall 14 is provided with a port 44, see FIGURE 2, for mounting a mid-range speaker 45, see FIGURE 6, the port 44 being covered with a grill cloth 46.

A mid-range frequency baffle 50 is disposed in the mid-range speaker compartment 36 and consists of a lower wall 51 of less length than the housing bottom wall 18 and located in vertical spaced relation thereto and parallel therewith; vertical walls 52, 53, with wall 52 being slightly of greater height than wall 53; and an upper inclined wall 54 extending from the upper horizontal edge of vertical wall 52 to the housing side wall 12, and secured thereto directly below the corresponding edge of the partition 32, see FIGURE 6. Of less length than the lower wall 51, is a horizontal wall 55 extending from the upper edge of vertical wall 53 and parallel to lower wall 51, and depending from the free edge of horizontal intermediate wall 55 is a depending vertical wall 56 having its lower free edge 57 spaced from the lower wall 51. Preferably all the walls 51-56 are of the same width with their inside edges secured to the rear housing wall 20.

The baffle 50 provides a circuitous passage P that starts above inclined wall 54 and extends between housing side wall 14 and vertical wall 52, between housing bottom wall 18 and lower wall 51, between vertical wall 53 and housing side wall 12, between baffle walls 54, 55 and 52, 56 to terminate in a tone chamber 58 within the confines of walls 51, 53, 55, 56. Provided in the rear wall 20 are two parallel vertical rows of openings 60, 61 that open directly into the tone chamber 58. The rows of openings 60, 61, are located adjacent end wall 53 of tone chamber 58.

As seen in FIGURE 6, the front of the housing 10 is open to provide access into the interior thereof and is closed by a removable front panel 64 held secured in place by the fastener elements 65. Disposed in the front panel 64 is a horizontal row of openings 68 which in the mounted position of the front panel open into the tone chamber 58.

For optional use with the speaker housing 10, a cabinet 70 is provided which consists of top and bottom walls 71, 72, and side walls 73, 74, joined together in rectangular form and provided with a front panel 75. Formed in the panel 75 are four ports 76, each mounting a low frequency speaker 80. The speakers are each located in a separate compartment provided by the intersecting partitions 81, 82, the ends of which terminate short of the opposed walls of the cabinet, see FIGURE 3, to provide a passage therearound. Extending across the ports 76 is a grill cloth 85. The rear of the cabinet 70 is open and the cabinet 70 may be mounted on the front panel 64 of the housing 10 in any desired manner. When so mounted, see FIGURE 5, the horizontal openings 68 in the front panel will communicate with the interior of the speaker cabinet 70.

It will be recognized that the sound waves emanating from the general function speakers 25, 29, will pass directly into the mid range speaker compartment 36 through openings 38, 39, to mix with the sound waves emanating from the mid range speaker 45. It is to be noted that the initial portion P' of the passage P into which the sound waves enter from openings 38, 39 increases in volume as it approaches the mid range speaker 45. This mixing of the sound waves equalize each other as they continue through the passage P into the tone chamber 58, from which they are directed outwardly through the openings 60, 61 in the rear wall 20 and the openings 68 in the front panel 64.

When the cabinet 70 with the low frequency speakers is mounted on the housing 10, the sound waves emanating from the low frequency speakers 80, will enter the initial portion P' of the passage P through the openings 68 to mix with the combined mix of the sound waves emanating from the speakers 25, 29 and 45.

Since the sound waves of all of the speakers, either in the housing 10 alone, or in addition to that from the speakers 80 of cabinet 70 when attached to housing 10, are directed through a single tone chamber, such has the effect of equalizing the tone of all of the speakers, whereby the sound produced thereby is directed outwardly through the openings 60, 61. Thus, a very efficient and compact acoustic tone equalizer enclosure has been provided which can be used for a wide variety of purposes in any audio system.

While certain novel features of my invention have been shown and described and are pointed out in the annexed claims, it will be understood that various omissions, substitutions and changes in the forms and details of the device illustrated and in its operation can be made by those skilled in the art without departing from the spirit of the invention.

Having thus described my invention, I claim as new and desire to secure by Letters Patent:

1. An acoustic tone equalizer comprising:

- (a) a rectangular housing having top and bottom walls, 40 side walls and a rear wall,
- (b) a removable closure panel forming the front wall of said housing,
- (c) a horizontal partition extending between said side walls defining within said housing upper and lower compartments of unequal size with the upper compartment smaller than the lower compartment,
- (d) a first port in each housing side wall between said partition and said housing top wall,
- (e) a general function speaker mounted at each first 50 port,
- (f) a divider extending downwardly at an inclination from the housing top wall, with its lower free end spaced from said partition, and located substantially mid-way between the transverse center of 55 said partition and an adjacent housing side wall,
- (g) a double transverse row of openings in said par-

tion below the free end of said divider with each row lying one on each side of a transverse vertical plane passing through said divider free end.

- (h) a second port in the housing side wall furthest remote from said transverse partition openings,
  - (i) a mid range speaker mounted at said second port,
  - (j) a baffle structure in said lower compartment providing a circuitous passage having an initial inlet portion of increasing volume and a terminal outlet portion defining a tone chamber, and
  - (k) at least one outlet opening in said rear housing wall positioned within the confines of said tone chamber.
2. The acoustic tone equalizer of claim 1, including:
- (a) at least one outlet opening in said front closure panel positioned within the confines of said tone chamber, and wherein
  - (b) said rows of partition openings are located to communicate with the smaller end of said passage initial inlet portion, and
  - (c) said mid range speaker lying opposite to the larger end of said passage initial inlet portion.
3. The acoustic tone equalizer of claim 2, wherein:
- (a) said circuitous passage is defined by planar wall sections of said baffle structure disposed parallel to the housing side walls and the housing bottom wall, and
  - (b) said initial inlet portion of said passage is defined by a planar wall section inclined with relation to said portion with one end thereof connected to the housing side wall opposite the mid range speaker and adjacent housing to the end of the partition secured to said housing side wall, and
  - (c) the other and lower end of said inclined wall section connected to the wall section parallel to the opposite housing side wall.
4. The acoustic tone equalizer of claim 3, wherein
- (a) said tone chamber is defined by wall sections of said baffle structure,
  - (b) the penultimate wall section lying below said inclined wall section and parallel to said housing bottom wall, and
  - (c) the terminal wall section lying parallel to the wall section opposite the housing side wall mounting the mid range speaker with its free end spaced from the wall section parallel to the housing bottom wall lying below said penultimate wall section.
